DESIGN FOR A CASKET SHELL

Alfred R. Christian, Chicago, Ill.

Original design application June 27, 1938, Serial
No. 78,093. Divided and this application August 12, 1938, Serial No. 79,288

Term of patent 3½ years

To all whom it may concern:

Be it known that I, Alfred R. Christian, a citizen of the United States, residing at Chicago, in the county of Cook and State of Illinois, have invented a new, original, and ornamental Design for a Casket Shell, of which the following is a specification, reference being had to the accompanying drawing, forming part thereof. This application is a division of my pending application, Serial No. D-78,093, filed June 27, 1938.

In the drawing,

Fig. 1 is a side elevation of a casket shell showing my new design;

Fig. 2 is an end elevation thereof.

I claim:

The ornamental design for a casket shell, as shown.

ALFRED R. CHRISTIAN.
